UNITED STATES PATENT OFFICE.

FRANK M. ASHLEY, OF BROOKLYN, NEW YORK.

VALVE.

942,045.

Specification of Letters Patent.

Patented Dec. 7, 1909.

Application filed July 28, 1900. Serial No. 25,130.

To all whom it may concern:

Be it known that I, FRANK M. ASHLEY, a citizen of the United States, residing at 63 Central Place, Brooklyn, in the county of 5 Kings and State of New York, have invented certain new and useful Improvements in Valves, of which the following is a full, clear, and exact specification.

This invention relates to valves and its object is to provide a simple and efficient construction of that type of valve wherein the valve seat can be removed for grinding or 10 cleaning, or for replacement by a new seat.

A further object is to provide a construction wherein the interior of the main valve-body will not require an exact finish by reason of the employment of a separate interior part or parts involving the removable valve seat, and the desired finish.

With the above and other purposes in view, the novel valve comprehends the improved construction set forth in the subsequent detailed description.

In the accompanying drawings forming part of this specification,—Figure 1, is a sectional view of a valve embodying my invention. Fig. 2, is a view of similar character illustrating a modification of a valve. Figs. 3 and 4, are plan and vertical sectional views respectively, of the seating proper. Figs. 5 and 6, are sectional and plan views respectively, of a modified form of the inner ring seating.

1, represents the body or casing having the usual inlet and outlet openings 2 and 3, interiorly threaded for the engagement of the pipes 4 and 5, the chamber within the casing being divided by a wall 6, containing the seat opening 7. Upon one side of the wall 6, is the bonnet opening 8, in which is fitted the cylinder 9, the latter having a lower annular portion resting on the wall 6, and surrounding the opening 7.

It will be noted that the wall 6, immediately surrounding its opening 7, embodies an annular raised seat 6^a, the lower end portion of the cylinder 9, containing in its under side, an annular groove which permits said portion to fit over said raised seat 6^a with the circular surface forming the opening in the said portion flush with the corresponding surface in the wall 6. The lower annular portion of the cylinder, also presents at its upper side a raised seat 10. 55 It will be advantageous to interpose a ring 12 of packing material between the seat 6^a,

and the grooved portion of the cylinder resting thereon, as such employment of the packing will obviate the necessity for accurately machining these parts. 60

13 refers to the usual cap or bonnet held in engagement with the valve-body either by screw threads 14 as shown in Fig. 1, or by means of an independent threaded ring 15, as indicated in Fig. 2, the cap in either instance acting to hold the cylinder down upon the wall 6, either by bearing directly upon the upper end of said cylinder or through an interposed ring 16, of packing material. The opening 17, is in one side of the cylinder to 70 furnish the requisite passageway. The valve stem may be adjustable in the cap 13, by threads 20, or otherwise. If preferred, the cylinder 9, may comprise a plurality of parts, Fig. 5, illustrating a construction 75 wherein the seat 10 is in one piece 35, and the body of the cylinder in another piece 36.

It will be seen that when the cylinder and its seat are removed for repair or for other purposes, the valve can still be used as the 80 character of the raised seating on the wall 6, and the lower face of the valve are such that the said valve will squarely, adequately and efficiently secure a bearing on said seating, the tightness of the joint being augmented 85 by the presence of a ring 19, of yielding material in the under side of the valve.

With a view of further preventing any turning of the cylinder and its seat, the cylinder body externally contains a vertical 90 groove 22, which as the cylinder is introduced in position, is adapted to have engaged therein a lug 23, integrally projecting from the contiguous part of the valve body.

The construction set forth is simple, 95 comparatively inexpensive and easily maintained in good condition.

Having now described my invention, what I claim as new and desire to secure by Letters Patent, is— 100

1. In a valve of the character described, the combination of a body portion having an internal lug at one side, said body portion also containing a dividing wall presenting an opening and raised ring seat surrounding 105 said opening, a cylinder with a groove engaged by said body-lug and with a lower portion embodying a raised ring seat and containing an under groove for receiving the seat of the dividing wall, the surface forming the opening in said lower portion being 110 flush with the corresponding surface in the

wall, a cap confining said cylinder and holding the lower seat portion in bearing engagement with the dividing wall, and a valve stem guided through the cap and carrying a 5 valve for coaction with either of said seats.

2. In a valve of the character described, the combination of a body portion having an internal lug at one side, said body portion also containing a dividing wall presenting 10 an opening and raised ring seat surrounding said opening, a cylinder with a groove engaged by said body lug and with a lower portion embodying a raised ring seat and containing an under groove for receiving the 15 seal of the dividing wall, the surface form-

ing the opening in said lower portion being flush with the corresponding surface in the wall, a cap confining said cylinder and holding the lower seat portion in bearing engagement with the dividing wall, and a valve 20 stem guided through the cap and carrying a valve for coaction with either of said ring seats, said valve having a yielding face.

In testimony whereof I affix my signature, in presence of two witnesses.

FRANK M. ASHLEY.
